means of space and air and fatty acids which are stored prior to being converted to a liquid form. The liquid is then applied to the pipe, and the pipe is then heated to a temperature of about 100° F. for a period of about 10 minutes. The pipe is then cooled and the liquid is removed.

UNITED STATES PATENT OFFICE

2,611,146

WIPER FOR DRILL PIPES HAVING A LUBRICANT CAVITY

John L. Buckley, Tenafly, N. J., assignor to United States Rubber Company, New York, N. Y., a corporation of New Jersey

Application December 20, 1947, Serial No. 792,902

2 Claims. (Cl. 15—210)

1

This invention relates to an improved soft elastic drill pipe wiper having special means embodied therein for retaining the mud-laden drilling fluid in the well casing and for lubricating the sliding surface of the drill pipe against the walls of the passage in the wiper to reduce the wear on the walls of the passage when the drill pipe is pulled out of or goes into the well.

The drill pipe wiper embodying the present invention is adapted to be installed in the usual manner above the top of the well casing, and below the floor of the rotary turn table which drives the drill pipe. However, the wiper may be attached to the rotary table above the master bushing as preferred by some drillers.

The wiper comprises a body which is made of soft elastic wear-resistant rubber, or rubber-like material, having a passage extending therethrough for the reception of the drill pipe, on which the mud-laden fluid is entrained upon being withdrawn from the well. The improvement comprises a cavity formed in the rubber body around the axis of the drill pipe passage which terminates in circular elastic lips adapted to fit under tension around the pipe. The lips wipe the mud-laden fluid from the pipe and collect and retain some of it in the cavity which acts as a lubricant between the sliding surfaces of the pipe and the lips when the pipe is pulled out of the well.

The outer edges of such lips are rounded to render them resistant to wear and tear, and the inside edges of the lips are provided with relatively square edges which efficiently remove the mud-laden drilling fluid from the drill pipe and cause it to flow back into the well casing. Some of the fluid is trapped in the cavity, while the excess flows back into the well between the rounded edge of the lower lip and the drill pipe. The trapped lubricating drilling fluid is available in the cavity to lubricate the drill pipe when it passes through the wiper. The coefficient of resistance between the dry surfaces of the wiper and the pipe is relatively high and it is important that such surfaces be lubricated to reduce the friction.

The wiper has the further advantage of permitting the enlargements on the pipe, such as the joints and protectors, if used, to pass with greater freedom through the wiper.

This invention is further described in connection with the accompanying drawings, in which:

Fig. 1 is a cross-sectional view of a drill pipe wiper embodying this invention, and shown in its operative position on the drill pipe, which is

being drawn from the well through the rotary table;

Fig. 2 is a cross-sectional view of the drill pipe wiper in its normal molded shape prior to being placed over the drill pipe; and

Fig. 3 is a plan view of a half-section of the wiper.

The drill pipe wiper 10 embodying this invention is placed over the drill pipe 11 in the usual manner, while the pipe 11 is supported on divided clamping slips (not shown) set in the divided master bushing 12 carried by the turn table 13, which rotates the pipe 11. In such position of the pipe the rim of the central passage 14 in the wiper is stretched over the top of the drill pipe. The pipe 11 is then supported by the derrick elevator, and is elevated slightly to permit the removal of the half-sections of the clamping slips and master bushing 12. The wiper 10 is then pushed, or lowered on the pipe 11 below the floor of the turn table 13, and the bushing 12 is replaced in the usual manner.

The joined drill pipe 11 may then be lowered into the well casing 15 through the blow-out preventor 16. In the downward movement of the drill pipe 11 the wiper stops against the blow-out preventor 16, and upon the withdrawal of the drill pipe the wiper is stopped against the master bushing 12. In either direction of the movement of the drill pipe 11, its joints 17 and the usual rubber protectors 18, if used, pass through the central passage or opening 14 in the wiper 10.

The wiper 10 comprises a soft resilient elastic rubber body 19 having a central passage 14 therein, which terminates at each side of the wiper in relatively thin flexible elastic lips 20 which fit tightly under the elastic tension of the rubber around the drill pipe 11. The passage 14 is enlarged between the lips 20 for the purpose of forming an interior cavity 21 within the body 19 of the wiper 10. The cavity surrounds the drill pipe 11, and is sealed thereby when the wiper is applied thereto. The wiper 10 is molded in the shape shown in Fig. 2, and it has a reinforcing metal ring 22 incorporated therein. The cavity 21 is provided for the purpose of trapping the mud-laden or drilling fluid which is entrained on the pipe 11 when it is withdrawn from the casing 15. The lips 20 have rounded edges 23 on the outside surfaces of the wiper, and they are provided with relatively sharp square edges 24 on the inside of the wiper.

When the drill pipe 11 is withdrawn from the pipe casing 15 in the direction indicated by the

arrow A in Fig. 1, the central portion of the wiper bends upwardly. The rounded edge 23 of the bottom lip 20 removes most of the large abrasive particles from the drilling fluid and permits some of the fine lubricating mud to pass between the lips and the pipe into the lubricating mud cavity 21. The square edge 24 on the upper lip removes substantially all of the remaining mud from the surface of the pipe and causes it to be entrapped in the cavity 21. The rounded edges remove most of the abrasive material from the mud-laden fluid before it enters the cavity 21, and thereby protect the sharp square edges 24 from being abraded by it.

The rounded edges 23 have the further advantage of increasing the tear resistance of the lips as well as protecting the less tear resistant square edges 24 from being torn by the passage through the lips of the pipe joints 17 or the protectors 18, if used. In performing that function the enlargements first engage the rounded edges which are resistant to tear. The sharp edge 24 on the first lip engaged is flexed away from the pipe and the sharp edge on the second lip through which the enlargement next passes is stretched and protected by the first lip engaged.

The portion of the drill pipe 11 pulled from the casing 15 may be coated with a thin film of the drilling fluid, and when allowed to stand in the derrick, the mud-laden film dries thereon. When the pipe is lowered into the well casing 15 the dry mud tends to abrade the outer edge of the upper lip, but as the edge 23 first contacted is rounded, the abrasive effect is reduced, and the dry mud is permitted to pass through into the interior cavity 21. The dry surface of the pipe 11 becomes lubricated by the wet mud, or liquid in the cavity 21 before such surface reaches the square edge 24 of the lower lip, which is then in contact with the pipe. The wall of the opening 14 in the wiper is thus protected against wear by the combination of the outer rounded edges 23 and the inner sharp edges 24 of the lips.

The rubber body 19 of the wiper 10 should be made of a vulcanized rubber compound including natural or synthetic rubber having relatively high abrasion resistance and elastic qualities, and in some cases should have resistance to deterioration by oil. It has been found that a neoprene oil resisting compound containing the conventional fillers such as carbon black and having a 40 to 50 durometer hardness will operate successfully. Such compounds may be varied to suit the conditions under which the wiper may be intended to operate.

While the preferred embodiment of this invention has been described and shown herein, it will

be understood that the details may be changed without departing from the spirit of this invention or the scope of the appended claims.

Having thus described my invention, what I claim and desire to protect by Letters Patent is:

1. A drill pipe wiper comprising a unitary soft elastic body having a passage therethrough adapted to receive a drill pipe, said passage terminating at each end thereof in a relatively flexible elastic lip adapted to be stretched over enlargements on the pipe and fit snugly around the pipe, said lips diverging outwardly from each other in their undeflected position and remaining separated when deflected by the pipe to form the walls of an enlarged portion of said passage between said lips during the movement of the drill pipe in either direction through said passage, and said enlarged portion of said passage being adapted to retain lubricating fluid therein which may be removed from the moving pipe and be entrapped in said enlarged portion.
2. A drill pipe wiper comprising a unitary soft elastic body having a passage therethrough adapted to receive a drill pipe, said passage terminating at each end thereof in a relatively flexible elastic lip adapted to be stretched over enlargements on the pipe and fit snugly around the pipe, said passage having an enlarged portion between said lips, said enlarged portion of said passage being adapted to retain lubricating fluid therein, which may be removed from the advancing pipe and be entrapped between said lips, each of said lips having an outer rounded edge and an inner sharp edge, whereby said rounded edge of one lip is flexed against the advancing surface of the pipe to remove the major portion of the lubricant in advance of said enlarged portion of the passage, and said sharp edge of the other lip is flexed against the surface of the pipe receding from the last mentioned rounded edge to entrap the finer particles of the fluid in said enlarged portion.

JOHN L. BUCKLEY.
